UNITED STATES PATENT OFFICE.

FRANCIS M. BARTON, OF CHICAGO, ILLINOIS, ASSIGNOR TO BARTON SPIDER WEB SYSTEM, OF CHICAGO, ILLINOIS, A CORPORATION OF ILLINOIS.

FORM FOR CONCRETE.

Application filed October 25, 1926. Serial No. 143,873.

The invention relates to hollow sheet metal forms for concrete floor constructions. One object of the invention is to provide an improved form of this type which is composed of units which may be nested in shipment and assembled at the place of installation, and which, when assembled, will be rigid. Another object of the invention is to provide an improved form of this type in which the units are formed of continuously corrugated sheets and in which the corners are stiffened or reinforced by integral formations. Another object of the invention is to provide an improved end plate for the form of corrugated metal. Another object is to provide an improved interlocking connection between the top and the sides of the form.

The invention consists in the several novel features hereinafter set forth and more particularly defined by claims at the conclusion hereof.

In the drawings: Fig. 1 is a vertical section through a floor embodying the invention. Fig. 2 is a section of the floor on line 2—2 of Fig. 1. Fig. 3 is a section on an enlarged scale taken on line 3—3 of Fig. 2. Fig. 4 is a section on an enlarged scale taken on line 4—4 of Fig. 1. Fig. 5 is a perspective of the form, the cover being separated for illustrative purposes. Figs. 6 and 7 are sectional views on an enlarged scale through one of the upper corners of the form. Fig. 8 is a perspective of a portion of one of the upper corners of the form. Fig. 9 is a detail section, showing the formation at the lower corners of the form.

The invention is exemplified in a concrete floor construction composed mainly of the beams 6 and a slab 7 extending over and uniting the beams to form an integral structure. The beams are usually reinforced by rods 8, extending lengthwise thereof and upwardly to a point in or adjacent the slabs. The forms which are disposed between the beams are made of sheet metal and comprise upper and lower members which, when secured together, form a hollow rigid box-like structure. Each of the upper and lower members is formed of a sheet of metal corrugated throughout its entire area. The lower member of each form comprises a bottom 9 and integral upwardly extending and flared side walls 10 and 11. The corrugations in the bottom are parallel and extend

between the sides 10 and 11, the metal being formed of a continuous series of alternating and reversely curved crowns 9^a, 9^b which are continued vertically in the side walls 10 and 11 to the upper margins thereof. In order to adapt the bottom to serve as a base or lath which is adapted to retain plaster 13, the transversely extending portions between the crowns are sheared, as at 9^c, and the sheared tongues 9^d are bent outwardly to form claws in the grooves in the outer face of the sheet. The claws 9^d on one side of each groove are staggered with respect to the claws on the opposite side of the groove, so that each claw will coat with a corrugated uncut portion of the sheet in retaining the plaster. In forming the lower member by bending the sides relatively to the bottom, the metal in the grooves at the corners is deflected outwardly or downwardly, as at 9^e, to permit the corrugated sheet to be bent without rupture, as more fully set forth in an application filed by me of even date herewith, Serial Number 143,062, to which reference may be had for a more detailed description of the method employed in producing the deformation. As a result of thus deflecting the metal at the base of the grooves, the corner is rendered exceptionally rigid, and pockets 9^f are produced which will cause the plaster to be effectively keyed around the lower corners of the form. The walls 10 and 11 are flared upwardly so that the concrete beam will be thicker adjacent its lower end than at its upper end, so the maximum will be disposed at the lower portion of the beam where the greatest stresses occur and the minimum adjacent the top of the beam. This extends the upper corners of the form to displace concrete which has little supporting value.

Each top member of the form consists of a sheet metal plate 17 which is corrugated from side to side and parallelly to the corrugations in the bottom 9 of the form. The side margin of each plate 17 is bent downwardly to form a flange 17^a adapted to lap the upper portion of the sides 10 and 11. The corrugations in the top are continued to the ends of said flanges, so that they will be corrugated conformably to the corrugations in the sides 10 and 11. The flanges are integral with the corrugated plate 17 and are formed by bending the plate in accordance with the method set forth in the aforesaid application No. 143,062, and so as to leave the

deformed portions 17^b across the corners of the grooves in the outer faces of the sheet to render the corner rigid. The crowns at the inner faces of the flanges 17^a are sheared, as at 17^c, and bent inwardly, as at 17^d, to form tongues which are adapted to lap the inner faces of the upper margins of the sides 10 and 11, so that the sides will be laterally locked between the flanges 17^a and said tongues. These top members form a support for the floor slab 7 and also serve as a connection between the upper ends of the sides 10 and 11 of the lower member of the form, so they will not spread.

Each form is usually built up of a plurality of sections, each comprising upper and lower members, the contiguous ends of which lap or extend into one another so that the form may be extended the full length of the beam or of the spaces desired between the beams and built up of small units which can be conveniently transported and handled. The upper flare on the sides of the lower members permits them to telescope into one another.

The end of each form is usually closed by a sheet metal plate 22 which is corrugated horizontally, so that it will render the ends of the form comparatively stiff. This plate is formed of a continuously corrugated sheet and has its margin sinuously sheared, as at 22^a, so that its edges will conform throughout its length to the inner faces of the aligned grooves in the inner faces of the bottom and sides 10 and 11. The upper and lower margins of the plate 22 are extended into grooves in the top and bottom of the form, so that it will be locked on all four sides to the form when it is assembled therein. This formation effects a fit between the plate and the member which forms a closure and renders unnecessary any special formation or die work on the plates for an interlock between all margins of the plates and the top, sides and bottom of the form.

In practice, the form members are fabricated at shops and shipped in stacks to the place where they are to be installed. The flared formation of the bottom members permits them to be telescoped or closely stacked for convenience in transportation or storage. At the place of installation, a suitable staging is erected to support the forms. The lower members are placed in lapped or telescoped endwise relation to extend the form to the desired length. Next, the end plates 22 are dropped into the lower members where desired, and then the top members are placed over the bottom members with the flanges 17^a on the outside of the sides 10 and 11, and the tongues 17^d at their inner faces. Thereupon, the form will constitute a rigid structure for forming a space or

hollow in the concrete. After the forms are in place, the concrete is poured between, around and over the forms to form an integral beam and floor construction, as well understood in the art. Next, the plaster is applied directly to the bottom of the forms and the beams, the claws 9^a serving to retain the plaster.

The invention exemplifies a form for a concrete floor construction in which the members are formed of continuously corrugated sheets with the corners deformed to render them rigid and so the metal will not be ruptured where it is bent to form the corners; also a form in which a completely corrugated end sheet is interlocked with the top and bottom members to stiffen the end of the form.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. A sheet metal form for concrete comprising a bottom and sides having a continuous series of corrugations extending upwardly in and to the upper edges of the sides, a cover consisting of a sheet of metal provided with marginal flanges having a continuous series of corrugations conforming to and fitting the corrugations in and lapping the sides.

2. A form for concrete comprising a single sheet of metal bent to form a bottom and sides provided with a continuous series of corrugations extending upwardly in and to the upper edges of the sides, a cover consisting of a sheet of metal provided with marginal flanges to lap the outer faces of the sides and having a series of corrugations conforming to and fitting the corrugations of the sides.

3. A form for concrete comprising a single sheet of metal bent to form a bottom and sides and having a continuous series of corrugations extending across the bottom and upwardly in the sides to the upper edges thereof, a cover consisting of a sheet of metal provided with marginal flanges to lap the sides, having a continuous series of corrugations extending continuously across it and downwardly in the flanges to their lower edges and conforming to and fitting the corrugations of the sides.

4. A sheet metal form for concrete comprising a bottom and sides having a continuous series of corrugations extending upwardly in and to the upper edges of the sides, a cover consisting of a sheet of metal provided with marginal flanges having a continuous series of corrugations conforming to and fitting the corrugations in and lap-

ping the outer face of the sides, and means to secure the sides against inward deflection.

5. A sheet metal form for concrete comprising a bottom and sides having a continuous series of corrugations extending upwardly in and to the upper edges of the sides, a cover consisting of a sheet of metal provided with marginal flanges having a continuous series of corrugations conforming to and fitting the corrugations in andlapping the outer faces of the sides and means integral with the flanges andlapping the inner faces of the sides respectively to secure said sides against inward deflection.

10 15 6. A sheet metal form for concrete comprising a bottom and sides provided with a continuous series of corrugations extending upwardly to their upper edges, and a cover consisting of a correspondingly corrugated sheet having flanges bent to fit and lap one face of the corrugated sides respectively and having integral tongues to lap the other faces of the sides.

7. A form for concrete comprising a single 25 sheet of metal bent to form a bottom and sides, with a continuous series of corrugations extending across the bottom and upwardly in the sides to their upper edges, and a cover consisting of a correspondingly corrugated sheet having flanges bent to fit and lap one face of the corrugated sides respectively and having integral tongues to lap the other faces of the sides.

30 35 8. A sheet metal form for concrete comprising a bottom and sides provided with a continuous series of corrugations extending to their upper edges, and a cover consisting of a correspondingly corrugated sheet having flanges bent to fit and lap one face of the corrugated sides and having integral tongues in the crowns of the corrugations at the inner faces of the flange to lap the other faces of the sides.

40 45 9. A sheet metal form for concrete comprising a bottom and sides and having a series of corrugations extending across the

bottom and throughout the sides, and an end plate continuously corrugated to its ends and having its ends curved transversely of the corrugations to fit in the grooves of the corrugations in the sides.

50 55 10. A sheet metal form for concrete comprising a bottom and sides and having a continuous series of corrugations extending across the bottom and throughout the sides and a correspondingly corrugated cover provided with flanges to top the sides, and an end plate continuously corrugated to its ends and having its ends curved to fit in the grooves of the corrugated sides and having top and bottom edges fitting in the grooves of the top and bottom respectively.

60 65 11. A form for concrete comprising a single sheet of metal bent to form a bottom and sides and having a continuous series of corrugations extending across the bottom and throughout the sides, the bottom being provided with outstruck claws disposed inwardly of the plane of the bottom crowns of the corrugations.

70 75 12. A form for concrete comprising a single sheet of metal bent to form a bottom and sides and having a continuous series of corrugations extending across the bottom and throughout the sides, the sides of the corrugations in the bottom being provided with outstruck claws disposed inwardly of the plane of the outer crowns of the corrugations.

80 85 13. A form for concrete comprising a single sheet of metal bent to form a bottom and sides and having a continuous series of corrugations extending across the bottom and throughout the sides, the sides of the corrugations in the bottom being provided with outstruck claws disposed inwardly of the plane of the outer crowns of the corrugations, the claws in the sides of the corrugations being staggered.

Signed at Chicago, Illinois, this 10th day 90 of May, 1926.

FRANCIS M. BARTON.
